UNITED STATES PATENT OFFICE

WILLIAM C. STEWART, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

HEEL-SEAT-FITTING MACHINE

Application filed November 7, 1923. Serial No. 673,379.

This invention relates to the manufacture of shoes and is disclosed as embodied in a heel seat fitting machine arranged to trim the peripheral portions of the heel seats of 5 shoes to which wood heels are subsequently to be attached.

In the manufacture of shoes to which wood heels are to be attached it is usual, prior to the attachment of the heels, to trim away the 10 surplus material from the periphery of the heel seat portions of the soles of the shoes so as to shape the soles to fit the concave heel seat surfaces of the wood heels. It is an object of the present invention to provide a machine 15 which will perform this operation in a satisfactory manner and with a minimum requirement of skill on the part of the operative. The herein disclosed machine not only fulfills these qualifications but is simple in construction, rapid in operation, and is adapted 20 for use upon shoes to which any of the various styles of wood heels are to be attached. With these objects in view the invention is herein disclosed as embodied in a heel seat fitting 25 machine having knives movable transversely of the sole of the shoe to be operated upon, from the edge of the sole inwardly, to make the heel breast receiving cuts, and having a knife operable after the breast cutting knives 30 have been withdrawn to complete the cutting operation by trimming the peripheral portion of the heel seat of the sole of the shoe from the heel breast receiving cuts toward the rear, thus removing an approximately horse- 35 shoe-shaped chip.

Features of the invention include mechanism for moving the knives which make the breast cuts alternately in either a straight path to fit the shoe for a full Louis heel or in 40 a curved path to fit the shoe for a Cuban heel or for any other heel which requires a concave breast cut; an organization of the machine by which the heel seat fitting knife is moved rectilinearly substantially at right 45 angles to the sole of the shoe to bring its cutting edge into engagement with the sole at the heel breast line after the heel breast receiving cuts have been made, and for thereafter causing relative movement of the knife 50 and the shoe to cause the knife to trim the

peripheral portion from the heel seat of the sole of the shoe; means for insuring an effective cutting action of the knife illustrated as comprising a roll engaging the sole of a shoe and operative to force the sole toward 55 the cutting edge of the knife; a crease plate operative to enter the rand crease of the shoe to deflect the edge portion of the heel seat of the sole of the shoe away from the shoe upper after the heel breast receiving cuts have been 60 made but before the trimming of the periphery of the heel seat; and a crease plate movable into the rand crease of the shoe before the making of the breast cut and out of the rand crease after the making of the breast cut 65 but before the trimming of the peripheral portion of the heel seat.

With the above and other objects and features in view, the invention will now be described with reference to the accompanying 70 drawings, which disclose a preferred embodiment thereof, and pointed out in the claims.

Figure 1 is a side elevation of a heel seat fitting machine embodying the present invention;

Fig. 2 is a plan view of the machine with the trimming mechanism removed;

Fig. 3 is a front elevation of the upper portion of the machine, showing the crease guides and breast cutting knives in inoperative position;

Figs. 4, 5 and 6 are front elevations of a portion of the machine, showing the crease guides and breast cutting knives in a series of positions which they assume during the 85 making of the breast cuts;

Fig. 7 is a side elevation partly in section, showing particularly the trimming knife and a roll utilized to control the stock during the heel seat fitting operation;

Figs. 8, 9 and 10 are detail views of said roll and its operating mechanism; and

Figs. 11, 12 and 13 are diagrammatic views indicating the sequence of operations of the machine and showing in Fig. 13 a shoe upon 95 which the heel seat fitting operation has been completed.

The illustrated machine is of a type arranged to remove a horseshoe-shaped strip of material from the heel seat of a shoe to 100

which a wood heel is to be subsequently attached, the machine being provided with a pair of knives moving transversely of the sole of the shoe to make the heel breast receiving 5 cuts at the forward extremity of the heel seat and with a trimming knife arranged to move from the heel breast line rearwardly, after the heel breast receiving cuts have been made, to complete the operation, the peripheral portion 10 of the heel seat of the sole being deflected away from the shoe upper while these cuts are made so that it may be trimmed from the sole by a rectilinear movement of the trimming knife.

15 The illustrated machine is provided with a column 16 having horizontal ways 18 in which is mounted a ram or sliding head 20. Column 16 serves also as a support for a motor 22 and is provided with suitable bearings for a main 20 power shaft 24 and a countershaft 26.

20 Mounted on vertical pivots 28 (Figs. 1, 2 and 7) near the top of the column of the machine is a pair of bell crank levers 30, each carrying at its forward extremity a rubber 25 gripping jaw 32. These jaws 32 constitute work supporting and clamping means and are arranged to grip a shoe 31 mounted on a last 33 between them, as indicated in Figs. 2 to 7, and for convenience in operating them a 30 treadle controlled link and lever system is provided. A sole 35 has already been attached to the shoe 31 and a breast covering flap 37 (Figs. 2 and 13) cut up from the sole. The jaw operating means comprises a treadle 35 (Fig. 1) fulcrumed at 36 to the base of column 16 and provided with a spring 38 tending to hold it in elevated position. A link 40 is connected at its lower end to treadle 34 and at its upper end, at 41 (Figs. 1, 2, 40 and 7), to the forwardly extending part of a bell crank lever 42. The bell crank lever 42 and a corresponding vertical arm 43 (Fig. 2) are clamped on a transverse shaft 44 having a bearing in the column 16. The arm 43 and 45 the upwardly extending arm of the bell crank lever 42 bear at 46 against the outwardly extending arms of the corresponding jaw-carrying bell crank levers 30 so that when treadle 34 is depressed, the outwardly extending 50 arms of bell crank levers 30 are moved forwardly and their forwardly extending arms, which carry the rubber jaws 32, move inwardly to grip the work. A pawl 48 (Fig. 1) is carried by treadle 34 and co-operates with 55 a rack 50 to hold treadle 34, and therefore jaws 32, in whatever position they may be placed. Pawl 48 is provided with a forwardly extending tail 52 which is engaged by 60 a compression spring 54 which tends to hold pawl 48 in engagement with rack 50 but permits its ready release by the foot of the operative. To facilitate proper positioning of the work in the machine, a back gage 60 65 (Figs. 1, 7, and 11) which may be adjusted

or controlled in any usual or convenient manner is carried to the rear of jaws 32.

As illustrated, gage 60 is connected at 62 (Fig. 11) to a slide 64 (Figs. 1 and 2), mounted on ways formed in or carried by column 16, and provided with a rack 65 operatively engaged by a pinion 66 mounted on a shaft 67 which carries also a hand lever 68 by means of which gage 60 may be adjusted. Shaft 67 may be secured in adjusted position by any suitable devices, and an indicator may be provided to indicate the position of gage 60. After the shoe 31 has been positioned in the machine with the rear of its counter portion against back gage 60 and has been securely gripped between jaws 32, the machine is operated to make the heel breast receiving cuts to form shoulders 72 (Fig. 13) against which the breast of the heel is subsequently to be positioned. For this purpose the machine 80 is provided with a pair of breast cutting knives 76 each of an L-shaped cross section and having two cutting edges substantially at right angles to each other (Figs. 2 to 6 and 11). These cutters 76 are each carried by a block 77 mounted for sliding movement in a way 78 pivoted at 80 to the upper end of a double armed lever 82 (Fig. 2), each guide or way 78 being provided with a tapered extremity forming a crease plate or guard 84 arranged to enter the rand crease of the shoe to protect the upper and support the edge 85 of the sole 35 during the making of the heel breast receiving cut. These levers 82 are pivoted as at 86 (Fig. 3) to collars 87, 88 carried by the upper end of a post 89 mounted for vertical sliding movement in ways 90 (Fig. 1) formed on or carried by column 16. A stop 92 positively limits downward movement of post 89 while a compression spring 94 supported by a bracket 96 carried by column 16 has its upper end housed in a socket 98 formed in the lower end of post 89 and thus tends to elevate the latter. Fulcrumed also at 86 to the upper end of post 89 is a pair of double bell crank levers 100 (Figs. 2 and 4), each of which is connected at its upper end by a pair of links 102 with the corresponding block 77 to which one of the knives 76 is rigidly secured. A compression spring 106 (Figs. 4, 5, and 6) bears at one end against each of the levers 82 and at the other end against the corresponding lever 100 keeping them normally separated. A threaded rod 108 (Figs. 4 and 7) is secured to each of the levers 82 and is provided with a nut 110 bearing against lever 100, which thus limits the relative movement of lever 82 and bell crank lever 100 under the action of spring 106. Tension springs 109 (Fig. 3) tend to move the inner ends of ways 78 downwardly to a position determined by arms 111 which are carried by ways 78 engaging the levers 82. The approximately horizontally extending arms of bell crank levers 100 are connected by a 130

pair of vertical rods 112 to a horizontal rod 114 (Fig. 1) carried by the forward extremity of a lever 116 fulcrumed at 119 to column 16. A link 120 connects lever 116 to a treadle 118 fulcrumed to the base of column 16. Link 120 is provided with a collar 122 which is engaged by the upper end of a spring 124 housed in a socket formed in the lower portion of the post 89, spring 124 thus tending to elevate rods 112. A second collar 128 carried by link 120 limits this elevating movement.

When treadle 118 is depressed, the forward end of lever 116 is swung downwardly. This lowers rods 112 and rocks levers 82 from the position of Fig. 3 to the position of Fig. 4, crease plates 84 entering the rand crease of the shoe and thereafter preventing further inward movement of levers 82 about pivots 86. During this period, post 89 is sustained against downward movement by spring 94. When crease plates 78 can no longer move toward each other, further depression of treadle 118 results in the bodily downward movement of post 89 with the consequent compression of spring 94. During this period, creases plates 78 rock about the rand crease of the shoe to the position illustrated in Fig. 5. When post 89 brings up against stop 92, continued depression of the treadle 118 and of rods 112 rocks bell crank levers 100 about their pivots 86, compressing springs 106 and forcing knives 76 into the edge 85 of the sole 35, with an inward and upward movement, to the position indicated in Fig. 6. When the treadle is released, the reverse movement takes place.

It will be noted that the movement of the knives 76, as just described, is such as to make a straight cut into the sole of the shoe. In fitting heel seats for shoes which are to be provided with Cuban or other straight heels, as distinguished from Louis heels, it is desirable that the breasting cuts be curved instead of straight so that they may correspond to the concave breast of those heels. With this in view, mechanism is provided for swinging the breast cutting knives 76 and a portion of their operating mechanism about a vertical axis as they make the breast cut. For this purpose, collars 87 and 88 are rotatably secured to post 89, so as to be capable of rotation about the axis thereof. Each of these collars is provided with a pair of lugs 140 (Figs. 1, 3 and 7) between which the forward ends of links 142 are secured to gimbal joints 143 (Fig. 3). The other ends of links 142 are connected by universal connections 144 to the lower ends of levers 146 (Figs. 1 and 2), the upper ends of which are pinned to a cross shaft 148 journaled in column 16. A rod 150 is pivoted at 152 to rod 120 so as to move downwardly with the latter when treadle 118 is depressed. At its upper end rod 150 passes through a slot in

a link 154, which is connected at one end to the lower end of one of the levers 146. A pair of lock nuts 156 prevent the escape of rod 150 through the slot in link 154. Thus the connection between rod 150 and link 154 has a certain amount of lost motion so that link 154 will not be affected by the preliminary portion of the downward movement of treadle 118. The other end of link 154 is provided with a head slideable in a curved slot 158 formed in a guide member 160 pivoted at 162 to column 16 and adjustable by means of a bolt 164 passing through a slot in the guide member. When in its extreme position, as shown in Fig. 1, the slot 158 of guide member 160 is positioned on the arc of a circle having as its center the pivotal connection of links 142 and levers 146. When adjusted, however, in a clockwise direction (as viewed in Fig. 1) from that position, the downward movement of link 154, as treadle 118 is depressed, forces the lower end of levers 146 rearwardly thus moving links 142 rearwardly and rotating collars 87 and 88 and the parts of the machine carried by them. This movement does not take place, on account of the lost motion of rod 150 and link 154, until knives 76 are just entering the edge of the sole. As they make their cut, they are thus rotated about a vertical axis and form the desired arcuate breast cut. The degree of curvature of the cut can of course be varied by the suitable adjustment of guide member 160 and, as before noted, when that member is in the position of Fig. 1, the cut made will be straight instead of curved. A spring 165 (Fig. 1) may be provided to ensure the return of the forward end of link 154 to its elevated position when treadle 118 is released.

After the breast cuts have been made in the sole and knives 76 have been returned to their inoperative position, the machine is operated to trim the peripheral portion of the heel seat so as to remove a horseshoe-shaped strip of material to form a bevel 170 (Fig. 13) in order to finish the heel seat fitting operation. This trimming operation is performed by the rearward movement of a knife 180 (Figs. 3 and 7) provided with a straight cutting edge 182, which, as the knife is moved rearwardly, enters upstanding corners 183 of the edge portion 85 of the sole 35 at the location of the breast cut, the sole at that time being in the condition indicated in Fig. 12. This knife is carried by the ram 20 (Fig. 1), which is given a reciprocating movement by power-operated mechanism under the control of a lever 184 fulcrumed to the column 16 at 186 and operated by means of a push rod 188 at the front of the machine. A tension spring 190 tends to hold lever 184 with its upper end inclined forwardly. Motor 22, through suitable gearing indicated generally at 192, rotates the main power shaft 24. This shaft 24

carries a clutch, which may conveniently be of the Horton type, having a dog controlled by arm 194 of lever 184. When it is desired to connect the clutch so as to operate the knife carrying ram 20, the operator pushes in the rod 188 to bring lever 184 to the position shown in Fig. 1. As long as lever 184 remains in the position indicated in Fig. 1, the clutch transmits power, but when the upper end of lever 184 is moved forwardly by the spring 190, the clutch, upon the completion of the revolution upon which it is then engaged, is disconnected. From the clutch power is transmitted through gearing 196 to shaft 26, the latter carrying a segmental flange 198 arranged to cooperate with a roll carried by the upper end of lever 184 to hold that lever in the position shown in Fig. 1 during something more than a complete revolution of the lower one of the gears 196 and shaft 24. Thus as soon as the machine has been started, the operator may release push rod 188 and the lever 184 will be held by the flange 198 to keep the clutch in engagement so that the machine will nevertheless complete its cycle of operation which requires two complete revolutions of shaft 24.

Shaft 26 carries upon it cams 200, 202 and 204. A roll 206 carried by a bell crank lever 208 engages the track of cam 200. The upper end of lever 208 is provided with a rack segment 210 co-operating with a rack bar 212 carried by ram 20 so that as cam 200 rotates the ram will be moved rearwardly, will then come to rest and will ultimately be moved back to its original position.

Ram 20 is provided at its forward extremity with a vertical guideway 216 (Figs. 1, 3 and 7) in which is mounted a vertically movable plunger 218. Plunger 218 is pivotally connected at 220 to the forward extremity of a bell crank lever 222 fulcrumed at 224 to ram 20. The other extremity of bell crank lever 222 is connected by a link 226 (Fig. 1) with a bell crank lever 228 fulcrumed at 230 to ram 20, one arm of the bell crank lever co-operating with link 226 to form a toggle mechanism. The other arm of bell crank lever 228 is connected by a link 232 to a block 234 fastened to a rod 236 mounted for sliding movement on ram 20. Block 234 is provided with a lug 237 extending into the path of movement of the upper end of a lever 240 fulcrumed to column 16 and provided at its lower end with a roll co-operating with the track of cam 202. The upper end of lever 240 is provided with a pair of contact members 242 and 244, the latter being in the form of a screw by means of which the distance between the contact members may be adjusted. Thus it will be seen that when lever 240 is rocked under the control of cam 202 and the ram is reciprocated under the control of cam 200, the upper end of the lever 240 will move forward until contact member 242 en-

gages lug 237 after which rod 236 will be moved forward and plunger 218 will be moved up and held in its upper position, cam 202 being provided with a circular portion for this purpose. Subsequently the upper end of lever 240 will be moved rearwardly relative to the ram 20 and contact member 244, when it reaches lug 237, will move bar 236 again to the rear, this resulting in the downward movement of plunger 218.

Plunger 218 carries at its lower end the knife 180 which thus moves in a rectilinear path substantially at right angles to the tread surface of the sole of the shoe to be operated on as it is brought into engagement with the sole at the heel breast line when plunger 218 is depressed and, during the subsequent rearward movement of ram 20, performs the trimming operation.

In order to support the edge of the sole during the trimming operation, the machine is provided with a plate 245 (Figs. 1, 3, and 12) mounted for sliding movement in ways 243 (Fig. 3) carried by column 16 and connected by a link 246 to the upper end of a bell crank lever 247 (Fig. 1) fulcrumed to column 16 and provided at its lower end with a roll engaging the track of cam 204. At its forward end plate 245 is provided with a horseshoe-shaped opening 248 (Fig. 2), the edge of this portion of the plate being beveled so as to enter the rand crease of the shoe and force the edge portion 85 of the sole 35 upwardly, as illustrated in Figs. 3 and 12 thus lifting the corners 183 into the path of the knife edge 182. For the purpose of ensuring effective control of the stock of the shoe sole during the trimming operation, a hold-down in the form of a toothed presser roll 250 (Figs. 7 and 8) is provided. This roll travels just to the rear of the knife 180 and during the trimming operation is rotated toward the knife (counter-clockwise as indicated by the arrow in Fig. 7) at a speed slightly faster than it would have if it simply rolled idly along the stock, so as to hold the stock pressed toward the knife edge. This roll 250 is keyed to a shaft 252 (see Fig. 7) mounted in bearings 253 carried by a spring-pressed plunger 254 housed in plunger 218. As illustrated in Fig. 8, a suitable friction device 251 may be used to prevent undesired movement of shaft 252. Thus roll 250 is held firmly in engagement with the sole of the shoe operated upon to depress the center of the heel seat out of the path of movement of the knife but may yield to compensate for variations in the thickness of the sole. In order to obtain the desired rotary movement, a pair of rack bars 256 and 257 (Fig. 9), held in rigid relation to one another by brackets 261, are pivoted at 255 to column 16 (Figs. 1 and 9) co-operating with pinions 258 and 259 mounted loosely upon shaft 252. Pinned to shaft 252 is a ratchet 260 (Figs. 9 and 10) co-operating with

70

5 a pair of spring-pressed pawls 262, 263 carried by pinions 258 and 259 respectively. Since the pinions 258 and 259 are slightly smaller than roll 250, the latter will have a peripheral velocity somewhat greater than it would have if rolling idly on the shoe sole and therefore will tend to feed the stock of the sole toward the cutting edge of knife 180 during the trimming operation. Moreover, 10 this pawl and ratchet mechanism causes roll 250 to feed the severed chip upwardly and forwardly away from and out of the way of the cutting edge of knife 180 during the forward movement of ram 20, the roll rotating 15 in the same direction (counter-clockwise as viewed in Fig. 7) during both the forward and rearward movement of ram 20.

While the operation of the herein disclosed machine has been pointed out in connection 20 with the description above, it will now be reviewed as a matter of convenience. The operative first locates the work, which consists of a shoe upon a last and having its out-sole but not its heel attached, with its counter 25 portion between the jaws 32 and with its back seam against gage 60. He then depresses the treadle 34 which causes the jaws 32 to grip the shoe, pawl 48 latching the treadle in depressed position. He next depresses treadle 30 118 which causes crease plates 84 and knives 76 to swing toward the shoe until crease plates 84 enter the rand crease of the shoe. Then the knives 76 and crease plates are rocked downwardly about the rand crease as 35 an axis and the knives 76 are moved inwardly and upwardly making the heel breast receiving cuts in the sole (as in Fig. 6). During this cutting operation the knives 76 will move in a straight line or will be rotated about a 40 vertical axis forward of their cutting edges according to the adjustment of guide member 160. After the heel breast receiving cuts have thus been made, treadle 118 is released and the rod 188 is pushed rearwardly tripping the 45 clutch and causing the power-operated parts of the machine to become effective. The ram 20 thus moves forwardly to the position indicated in Fig. 1 and the cam-operated lever 240, straightening the toggle 226, 228, causes 50 the plunger 218, carrying knife 180 and the roll 250, to move downward to bring the cutting edge 182 of the knife 180 into engagement with the sole of the shoe adjacent to and just forward of the location of the heel 55 breast cuts which have been previously made. While this is taking place, crease plate 245 moves forward and enters the rand crease of the shoe, deflecting the peripheral portion of the heel seat of the sole of the shoe upwardly, 60 as shown in Fig 12, into the path of the horizontally moving knife edge 182. The ram 20 is next moved rearwardly causing knife 180 to trim off the upwardly deflected periphery of the heel seat portion of the sole. During 65 this operation roll 250 is positively rotated

in a counter-clockwise direction, as viewed in Fig. 7, at a speed slightly greater than it would have if rolling idly so as to tend to force the sole toward the cutting edge of the knife 180. After knife 180 has finished its cutting operation and has passed the rear of the work, cam-operated lever 240 breaks the toggle 226, 228 so that the plunger 218 is elevated, raising the knife 180 and the roll 250 with it as the machine comes to rest. Crease plate 245 is withdrawn by the cam 204 at the proper time and treadle 34 may then be released and the shoe removed.

Having described the invention, what I claim as new and desire to secure by Letters 80 Patent of the United States is:—

1. A heel seat fitting machine having, in combination, means for deflecting the peripheral portion of the heel seat of the sole of a shoe, a knife, means for causing relative movement of the knife and the sole in a direction substantially at right angles to the tread surface of the sole to bring the cutting edge of the knife into engagement with the sole at its heel breast line, and means for causing relative movement of the knife and the sole in another direction to cause the knife to trim off surplus material from the sole from the heel breast line rearwardly.

2. A heel seat fitting machine having, in combination, means for deflecting the peripheral portion of the heel seat of the sole of a shoe, a knife, means for causing relative movement of the knife and the shoe in a direction substantially at right angles to the sole of the shoe to bring the cutting edge of the knife into engagement with the sole of the shoe at the heel breast line, and means for causing relative rearward movement of the knife and the shoe to cause the knife to trim 100 surplus material from the peripheral portion of the heel seat of the sole of the shoe.

3. A heel seat fitting machine having, in combination, a knife, means for supporting a shoe in operative relation thereto, and means for moving the knife substantially at right angles to the tread surface of the sole of the shoe to bring the cutting edge of the knife into engagement with the sole of the shoe and for thereafter moving the knife to trim 110 surplus material from the peripheral portion of the heel seat of the sole.

4. A heel seat fitting machine having, in combination, a knife, means for supporting a shoe in operative relation thereto, and means for moving the knife substantially at right angles to the sole of the shoe to bring the cutting edge of the knife into engagement with the sole at the heel breast line and for thereafter moving the knife rearwardly to trim surplus material from the peripheral portion of the heel seat of the sole.

5. A heel seat fitting machine having, in combination, a hold-down member arranged to engage the sole of a shoe and a knife, the 130

- hold-down member and the knife being arranged to move substantially at right angles to the tread surface of the sole of the shoe to bring them into engagement with the sole of the shoe, and means for thereafter moving the knife to cause it to trim surplus material from the peripheral portion of the heel seat of the sole.
6. A heel seat fitting machine having, in combination, means for supporting a shoe sole with the peripheral portion of its heel seat deflected, a knife having a blade formed as a portion of a cylindrical surface with its axis transverse to the sole of the shoe, means for moving the knife blade substantially at right angles to the sole to bring its cutting edge into engagement with the sole at the heel breast line, and means for moving the knife rearwardly to cause it to trim surplus material from the peripheral portion of the heel seat of the sole.
7. A heel seat fitting machine having, in combination, means for supporting a shoe sole with the peripheral portion of its heel seat deflected, a knife having a straight cutting edge and a blade formed as a portion of a cylindrical surface with its axis transverse to the sole of the shoe, means for causing relative movement of the knife and the shoe substantially at right angles to the sole of the shoe to bring the cutting edge of the knife into engagement with the sole at the heel breast line, and means for causing relative movement of the knife and the shoe to cause the knife to trim surplus material from the deflected portion of the sole from the heel breast line rearwardly.
8. A heel seat fitting machine having, in combination, a knife, means for causing relative movement of the knife and a shoe sole to bring the knife into engagement with the sole at its heel breast line, a roll adjacent to the cutting edge of the knife, means for deflecting the peripheral portion of the heel seat of the sole, and gearing arranged to rotate the roll to cause it to feed the sole toward the cutting edge of the knife to trim surplus material from the peripheral portion of the heel seat of the sole.
9. A machine for operating upon shoes having, in combination, a knife, and a roll movable together across the work to perform a cutting operation, said roll being operative to feed the work toward the cutting edge of the knife and, after the cutting operation is completed, to feed the material severed from the work away from the cutting edge of the knife.
10. A machine for operating upon shoes having, in combination, a knife having a straight cutting edge, a roll located adjacent to the cutting edge of the knife and with its axis substantially parallel to said cutting edge, and means for rotating the roll toward the cutting edge of the knife to force the work toward said cutting edge during the cutting operation and to feed the chip severed from the work away from the cutting edge of the knife after the completion of the cutting operation.
11. A machine for operating upon shoes having, in combination, a knife, a roll adjacent to the cutting edge of the knife, means independent of said roll for causing relative movement of the knife and roll and the work along the face of the work to cause the knife to perform a cutting operation upon the work, means for rotating the roll during said relative movement to force the work toward the cutting edge of the knife, and means for rotating the roll in the same direction after the completion of the cutting operation to feed the chip severed from the work away from the cutting edge of the knife.
12. A heel seat fitting machine having, in combination, a work support, a knife, means for moving the knife relatively to a shoe on the work support in a path substantially parallel to the surface of the sole of the shoe and extending from the heel breast line rearwardly substantially to the heel end of the sole to cause the knife to sever the peripheral portion from the heel seat of the sole of said shoe, a roll arranged to engage the sole of said shoe, and means for rotating the roll to cause the sole engaging portion of the roll to force the sole of the shoe forwardly toward the cutting edge of the knife.
13. A heel seat fitting machine having, in combination, a knife, a roll adjacent to the cutting edge of the knife, means for moving the knife and the roll rearwardly of the shoe to trim away surplus material from the periphery of the heel seat of the sole of the shoe, and gearing arranged to rotate the roll to cause it to force the sole of the shoe toward the cutting edge of the knife as the roll and the knife move toward the rear of the shoe.
14. A heel seat fitting machine having, in combination, a knife, a roll adjacent to the cutting edge of the knife, means for moving the knife and the roll toward the rear of the shoe to trim surplus material from the periphery of the heel seat of the sole of the shoe, and mechanism arranged to cause the roll to force the sole of the shoe toward the knife edge as the trimming operation is performed.
15. A heel seat fitting machine having, in combination, a crease plate arranged to enter the rand crease of a shoe, a slide substantially at right angles to the crease plate, a knife and a roll carried by said slide and movable therewith to cause the roll to contact with the sole of a shoe positioned with said crease plate in its rand crease and to bring the cutting edge of the knife into engagement with the sole of the shoe at its heel breast line, means for moving the slide rearwardly to cause the knife to trim surplus material from the periphery of the heel seat of the sole of the shoe.

riphery of the heel seat portion of the sole of the shoe, and gearing arranged to cause the roll to force the sole of the shoe toward the cutting edge of the knife as the roll and the 5 knife move rearwardly.

16. A heel seat fitting machine having, in combination, means for supporting a shoe, a knife having a straight cutting edge and a blade formed as a portion of a cylindrical 10 surface having an axis arranged transversely of the shoe, means for moving the knife to bring its cutting edge into engagement with the sole of the shoe at the heel breast line and for thereafter moving the knife rearwardly 15 to trim surplus material from the peripheral portion of the heel seat of the sole of the shoe, a roll arranged to engage the sole of the shoe adjacent to the cutting edge of the knife, and means for rotating the roll to cause it to tend 20 to move the sole of the shoe toward the cutting edge of the blade of the knife.

17. A heel seat fitting machine having, in combination, a hold-down roll arranged to engage the sole of a shoe and a knife formed 25 with a straight cutting edge and a curved blade, the knife and the roll being arranged to move substantially at right angles to the sole of the shoe to bring the roll and the cutting edge of the knife into engagement with 30 the sole of the shoe and to position the cutting edge of the knife at the heel breast line of the sole, and means thereafter to move the roll and the knife rearwardly to cause the knife to trim surplus material from the peripheral 35 portion of the heel seat of the sole while the roll depresses the central portion of the heel seat out of the path of movement of the knife.

18. A heel seat fitting machine having, in combination, a knife having a blade formed as a portion of a cylindrical surface, means for moving the knife to bring its cutting edge into engagement with the sole of a shoe, a roll adjacent to the cutting edge of the knife, a 40 gear member coaxial with the roll, means for moving the knife and the roll toward the rear of the shoe to trim surplus material from the periphery of the heel seat of the sole of the shoe, and a co-operating gear member 45 engaging the first-named gear member and operative to cause the roll to force the sole of the shoe toward the knife edge as the trimming operation is performed.

19. A machine for operating upon shoes 50 having, in combination, a feed roll for forcing the work toward an operating instrumentality, and means for operating the roll comprising a shaft to which the roll is secured, a pair of pinions loose upon the shaft, a rack 55 bar engaging each pinion, a ratchet fast upon the shaft, a pawl carried by each pinion and spring-pressed toward and engaging the ratchet, and means for causing relative movement of the pinions and the rack bars to 60 effect rotation of the feed roll in the same di-

rection independent of the direction of rotation of the pinions.

20. A machine for operating upon shoes having a feed roll arranged to feed the work toward an operating instrumentality and 70 means for rotating said roll comprising a shaft to which the roll is secured, a pair of members loose upon the shaft, a ratchet secured to the shaft, a pawl carried by each of said members and spring-pressed toward 75 and into engagement with said ratchet, and means for reversibly rotating said members in opposite directions so that the rotary movement of said roll will be always in the same direction independent of the direction of rotation of said members. 80

21. A heel seat fitting machine having, in combination, a knife arranged to make a breast cut in the sole of a shoe, and a plate adjacent to and movable with the knife arranged to enter the rand crease of the shoe before the cutting operation of the knife. 85

22. A heel seat fitting machine having, in combination, a knife, means for operating the knife to make a heel breast receiving cut in 90 the sole of a shoe, and a plate movable into the rand crease of the shoe before the cutting operation of the knife and formed and arranged to protect the shoe upper and to deflect the edge of the sole from the shoe upper during 95 the cutting operation.

23. A machine for operating upon the heel seat portion of the sole of a shoe having, in combination, work supporting and clamping means, a crease plate, means for moving the crease plate in the direction of the length of the shoe to cause the crease plate to enter the rand crease of a shoe carried by said supporting means, and means for thereafter operating upon the heel seat portion of the 100 shoe. 105

24. A heel seat fitting machine having, in combination, means for supporting a shoe in operative position, a crease plate having an approximately horseshoe shaped opening 110 therein, means for moving the crease plate from a position outside the work when the latter is supported in operative position to cause the horseshoe-shape edge of the crease plate to enter the rand crease of a shoe carried by the supporting means, and means for trimming the peripheral portion of the heel seat of the sole of the shoe. 115

25. A heel seat fitting machine having, in combination, a work support, a knife arranged to make a heel breast receiving cut in the sole of a shoe carried by the work support, a crease plate, means for moving the crease plate to cause it to enter the rand crease of the shoe carried by the support after the making of the heel breast receiving cut, and means for trimming the peripheral portion of the heel seat of the sole of the shoe while the latter is supported by the crease plate. 120 125

26. A heel seat fitting machine having, 130

in combination, a knife arranged to make a heel breast receiving cut, a plate movable with the knife and arranged to enter the rand crease of the shoe prior to the cutting operation of the knife, and a support for the plate and the knife arranged for movement laterally of the shoe to cause said plate to enter the rand crease of the shoe and thereafter to rock about an axis extending in the general direction of the length of the shoe to cause the knife as it cuts to move in a path of an angle to the surface of the sole of the shoe so as to emerge from the sole before it has passed completely across the sole.

27. A heel seat fitting machine having, in combination, a support for a shoe, a pair of knives arranged to make heel breast receiving cuts in the sole of a shoe carried by the support, means for moving the knives laterally of the sole to bring their cutting edges into engagement with the periphery of the sole at the heel breast line, means for thereafter rocking each knife about an axis arranged longitudinally of the shoe to cause the knives to point away from the shoe upper, and means for moving the knives toward each other while so pointed to make the heel breast receiving cuts.

28. A machine for operating upon shoes having, in combination, a feed roll for forcing the work toward an operating instrumentality, means for moving said operating instrumentality back and forth across the work arranged to cause it to be in operative engagement with the work during a part of said movement, and means for operating said feed roll constructed and arranged continuously to rotate the feed roll in the same direction during movement of the operating instrumentality regardless of the direction of movement of the latter.

29. A heel seat fitting machine having, in combination, means for supporting a shoe in operative position, means for distorting the periphery of the sole of a shoe which is held by said supporting means, said distorting means being movable from a point outside the work into the rand crease of the shoe, and trimming means arranged to cut away the distorted peripheral portion of the heel seat of the sole of the shoe.

30. A heel seat fitting machine arranged to operate upon the sole of a shoe having, in combination, cutting means movable transversely of the sole to make a cut substantially at the heel breast line, means for supporting a shoe in operative relation to said cutting means, means movable from a point outside the shoe while it is so supported into the rand crease of the shoe to distort the peripheral portion of the sole thereof, and trimming means for removing the distorted peripheral portion of the heel seat of the shoe.

31. A heel seat fitting machine having, in combination, a cutter and a guide arranged

for movement together in a direction transverse to the length of the sole of a shoe to bring the guide into the rand crease of the shoe to protect the upper of the shoe, said cutter being movable with respect to the guide, and arranged to make a cut through the edge of the sole transversely of the sole adjacent to the heel-breast line to form a shoulder for co-operation with the corresponding part of a heel to be attached to the shoe.

32. A heel seat fitting machine having, in combination, a support for a shoe, a cutter and a guide mounted for conjoint movement in a path curved about an axis outside of the surface of the sole of a shoe carried on said support to bring the forward end of the guide into engagement with the rand crease of the shoe, and means for continuing the movement of the knife through the edge of the sole to form a shoulder adjacent to the heel-breast line while the upper of the shoe is protected by said guide.

33. A heel seat fitting machine having, in combination, a shoe support, a guide movable laterally of the shoe support and provided with a projecting forward edge adapted to be brought into engagement with the rand crease of a shoe upon said support, a cutter movably supported upon and guided by said guide, said cutter being movable inwardly with the guide and adapted to pass through the edge of the sole of the shoe to form a shoulder therein adjacent to the heel-breast line, means for moving said cutter and guide, and means for connecting said cutter and guide constructed and arranged to permit a cessation of movement of the guide when it comes into engagement with the shoe while the movement of the cutter is continued to cause it to pass through a portion of the sole of the shoe.

34. A machine for operating upon the soles of shoes having, in combination, a support for a shoe to be operated upon, a pair of guards arranged for movement into engagement with the upper and the attaching surface of the sole of a shoe upon the support at opposite ends of the heel breast line, a pair of knives adjacent to the respective guards, and means for moving the knives and guards together toward the shoe until the guards are brought into engagement with the shoe and for thereafter moving the knives relatively to the guards to cut the sole of the shoe to form a pair of shoulders formed to receive a heel to be attached to the shoe to position the heel longitudinally of the shoe.

35. A machine for operating upon the soles of shoes having, in combination, a work support, means for positioning a shoe upon the support relatively to the operating instrumentalities of the machine, a pair of plates movable toward and from the shoe in a direction substantially transverse of the sole of the shoe to position the plates in engagement with

the upper and the attaching surface of the sole of a shoe upon the support adjacent to its heel breast line, a pair of knives, one upon each side of the shoe, and means for moving the knives and the plates toward the shoe until the plates engage the shoe and come to rest and for thereafter moving the knives relatively to the plates to cut a pair of heel engaging surfaces upon the sole of a shoe.

36. A heel-seat fitting machine having, in combination, a knife arranged to make a heel-breast-receiving cut, a plate movable with the knife and arranged to enter the rand crease of a shoe prior to the cutting operation of the knife, and a support for the plate and the knife arranged for movement laterally of the shoe to cause the plate to enter the rand crease of the shoe and thereafter to rock about an axis extending heightwise of the sole of the shoe to cause the knife to move in a curved path.

37. A heel-seat fitting machine having, in combination, a knife arranged to make a heel-breast-receiving cut, a plate movable with the knife and arranged to enter the rand crease of a shoe prior to the cutting operation of the knife, and a support for the plate and the knife arranged for movement laterally of the shoe to cause said plate to enter the rand crease of the shoe and thereafter to rock about an axis extending in a general direction of the length of the shoe as well as about an axis extending heightwise of the shoe to cause the knife as it cuts to move in a curved path at an angle to the surface of the sole of the shoe in such a manner as to emerge from the sole before it has passed completely across the sole.

38. A heel-seat fitting machine having, in combination, a support for a shoe, a pair of knives arranged to make heel-breast-receiving cuts in the sole of a shoe carried by the support, means for moving the knives laterally of the sole to bring their cutting edges into engagement with the periphery of the sole at the heel-breast line, means for thereafter rocking each knife about an axis arranged longitudinally of the shoe to cause the knife to be pointed away from the shoe upper, means for moving the knives toward each other while so pointed to make heel-breast-receiving cuts, and means to rock the knives about an axis extending heightwise of the shoe to cause the knives to move in a curved path as they make said cuts.

In testimony whereof I have signed my name to this specification.

WILLIAM C. STEWART.
